**INTERLOCKED OPEN KEYBOARDS WITH
ELECTRIC RESTORING**

Gordon Herbert May, San Jose, Calif., assignor to International Business Machines Corporation, New York, N.Y., a corporation of New York

Filed Oct. 25, 1961, Ser. No. 147,656
8 Claims. (Cl. 235—145)

The invention relates to keyboards, and it particularly pertains to open keyboards for higher speed entering of data into accounting and other business machines, although it is not limited to such machines.

There are many business machines which have manually operated keyboards as the data input means. Such keyboards can be classified in many ways. For instance, adding machines are frequency classified as 10-key and 81-key or full-keyboard machines. The type of key response is sometimes used to classify machines having keyboards as, for example: key drive machines and conditioning key machines. At other times is it convenient to classify machines as to closed type keyboards or open type keyboards. The term closed keyboard, as used hereinafter, is construed as a keyboard that is interlocked in such a way that the operator must lift his finger from a depressed key before the next key can be depressed. This type of keyboard is slower than the open keyboard, since any possible key stroke overlap is substantially eliminated. In this type of keyboard there is no provision to insure against blank column mistakes. The term open keyboard as used hereinafter, is construed as any type of keyboard which allows the operator to depress two or more keys simultaneously. Such keyboards usually have no provisions to insure against double character keying or blank column mistakes.

The invention is concerned with a hybrid type keyboard termed hereinafter an interlocked open keyboard with electric restoring, which inhibits simultaneous keying, but allows the operator to have two or more keys depressed at the same time, providing the keys were depressed in sequence. In this keyboard double character keying is inhibited by the interlock and blank column mistakes are eliminated, since the electrically operated restore bail cannot function until an entry has been made. As used hereinafter, the term interlock is construed as any device or mechanism which makes it impossible to key two characters simultaneously; that is, to enter the corresponding function whether or not more than one key may be depressed at a given time.

The prior art is replete with excellent keyboards of many different designs. However, these prior art keyboards are subject to improvement in several features. The key stroke is often overly stiff and frequently the design is such that servicing is difficult and adjustments are particularly hard to carry out. Prior attempts to overcome these shortcomings have resulted in excessively complex and expensive keyboards.

An object of the invention is to provide an open keyboard with interlocking and electrical restoring which has a good key stroke, being neither too sensitive nor too stiff, and having good operator feedback.

Another object of the invention is to provide a keyboard having all major functional parts readily accessible for servicing, with the parts particularly simplified and accessible for adjustment.

A further object of the invention is to provide a keyboard with a minimum number of parts and at lower cost than the prior art keyboards.

A still further object of the invention is to provide an interlocked open keyboard with electric restoring having as wide a flexibility of application as possible.

2

According to the invention an interlocked open keyboard with electric restoring comprises a more or less conventional frame, a plurality of cross members in the frame, an interlock assembly on a cross member or itself a cross member, but two spring assemblies on cross members and a switch actuated by a plurality of key sections with each section having but two bars biased by resilient members of the two spring assemblies. Each key section has one key bar supported by a pair of cantilever spring portions, which preferably are parts of a unitary spring assembly, affording strictly parallel key bar translation with light, but positive key action. Each key section has one selection bar having a shoulder bearing in a home position against a cross member in the frame of the keyboard under the urging of a leaf spring portion, which may be a part of an integral assembly. The cooperating key and selection bars also have camming surfaces arranged for tripping the selection bar off the shoulder under depression of the key bar for driving the selection bar into an active position under the urging of the leaf spring portion. The camming surfaces are also arranged in such manner that while one selection bar is in the active position and all other selection bars are held out of the active position by the interlock mechanism, another associated key bar may be depressed to drive the cooperating selection bar against the interlock under the urging of one of the two spring assemblies in a ready position in readiness for immediate movement into the active position upon restoration of the previously activated selection bar by the electric restoring bail. Preferably a resilient extension of the one of the cantilever spring members is used to perform the functions of tripping the selection bar off the shoulder bearing on the cross member in the frame and bowing to permit depressing the associated key bar and readying the selection bar for movement into the active position.

The keyboards according to the invention are particularly suitable, although not limited to, the operation of switching matrices of the types involving electric magnetic or optic circuit paths, and further according to the invention an electric switch contact assembly comprises a plurality of contact bars, preferably having silver alloy blade strips for making the actual contact with silver alloy blades carried by the selection bars. The contact making blades on the selection bars are molded in insulating material and comprise a comb shaped silver alloy blade strip. Pilot holes in the insulating material permit the drilling out of portions of the comb to isolate portions of the contact making blades from the remainder of the comb assembly and drilling of other holes into which wires may be soldered to connect groups of isolated blade portions in the insulating material to provide special switching circuitry, such as for dual code outputs.

Still further according to the invention the key bars and the selection bars are arranged in parallel extending narrow slots in the cross members of the frame and are held in place solely by pressure of the two spring assemblies, whereby the parts are readily snapped into place and can be instantly removed for servicing. Little adjustment is needed in the arrangement shown, but adequate space is permitted for entering the necessary tools and jigs, while at the same time retaining the compactness and simplicity of the principal structure.

In order that important advantages of the invention may be readily attained in practice, several preferred embodiments of the invention, given by way of examples only, are described hereinafter with reference to the accompanying drawing forming a part of the specification and in which:

FIG. 1 is an assembly view of a keyboard according to the invention;

FIG. 2 is an illustration of a key section and the operation thereof according to the invention:

FIG. 3 is an illustration of another key section according to the invention;

FIG. 4 shows details of key sections as shown assembled in FIG. 1; and

FIG. 5 is an illustration of electric switch contact parts according to the invention.

FIG. 1 depicts an open keyboard according to the invention having a plurality of keys 10 interlocked so that only one key may be completely depressed at a given instant to actuate electric contacts 12 or perform some other desired function, examples of which will be described hereinafter. One of the remaining keys 10 may also be depressed after restoration of the first key to the home position; a further key 10 may be depressed after restoration of the one key; and so on. The restoring mechanism conventionally restores much faster than the normal keying speed of the operator so that the maximum key stroke overlap is available without slowing the keying speed. According to the invention the keyboard is arranged so that a later operated key will complete the desired function immediately upon the restoration of the earlier operated key.

Because the operators of accounting and other machines having such keyboards usually refer to the visible buttons or key tops themselves as "keys," the key tops 14 were generally indicated as keys 10, but hereinafter the buttons themselves will be referred to as key tops 14, and the term keys will be used only in a general sense.

A keyboard according to the invention is arranged in a more or less conventional frame 16, of which a back-plate 18 and one end plate 19 only are partially shown, with four cross members 21-24. The key bar cross members 21 and 22 have a plurality of parallel arranged slots 31 and 32, respectively, arranged therein to receive key bars 36. The key bars 36 are urged upward in the operating slots 31 and 32 by means of a resilient member assembly having cantilever restoring spring portions 41 and 42. A number of selection bars 46 are arranged for horizontal movement in confining slots 33 and 34 in selection bar cross members 23 and 24, respectively. The selection bars 46 are urged forward by means of a resilient member assembly having driving spring fingers 52. A conventional ball interlock assembly shown as comprising the cross member 23 having a raceway 56 in which a plurality of balls 58 permits only one of the selection bars 46 to be moved downward into the tripped position off the cross member 23. No other one of the selection bars 46 can be propelled into the downward position until the previously activated selection bar 46 is restored by means of a restoring bail 60, which is arranged to return the selection bar 46 to the home position against the bias of the resilient member 52.

For clarity the invention will be described now with reference to figures showing but one or two key sections. The term key section as employed herein is construed to be that portion of a keyboard comprising a key top, a key bar, a selection bar, and a proportionate part of each of the cross members, spring assemblies, interlock assembly and switch assembly, as necessary to perform the desired function.

FIG. 2 shows a key section according to the invention. The key bar 36' has depending pin portions 61 and 62 which are inserted in holes in the cantilever spring portions 41', 42' of a unitary spring assembly 40'. The spring assembly 40' supports the key bar 36' and urges it into the home position at the top of the confining slots 31 and 32 in the crossbars 21 and 22, and further confines the movement of key bar 36' to strictly vertical movement. All of the key bars 36' in the switchboard arrangement are identical, except for the location of the key stem and the surmounting key top 14. As shown, the key top 14 is almost directly over the support pins 61 and 62, but as also shown in phantom other key stem positions are used

without detracting from the parallel translation afforded by the cantilever spring members 41' and 42'. The key bars 36' are readily removed and inserted into the keyboard arrangement without difficulty by the technician. It is merely necessary to deflect the spring members 41', 42' to disengage the support pin portions 61' and 62', and move the key bar 36' to the rear far enough to remove it from the forward cross member slot 31; no special tools are needed. A depending portion 64' of the key bar 36' having a camming surface 65' is arranged to trip the selection bar 46' off of a camming surfaced shoulder portion 66' of the cross member 54' of the interlock assembly where it is urged to the home position by the resilient spring member 52', which is held to the frame by a cross member 23'. As shown in FIG. 2(b) a depression of the key top 14 moves the key bar 36' downward and the tip of the camming portion 65' nudges the selection bar 46' off the shoulder permitting it to go forward under urging of the resilient member 52', and allowing it to drop down between the balls 58 provided no other selection bar is so active. Depressing any other key top 14 will be of no avail since the ball interlock assembly will prevent the corresponding selection bar 46' from entering the interlock and going downward to trip and uncover the apertures in the light switch 12'. Pressure need not be removed from the other key top 14, however, as the camming surfaces 65' and 66' are arranged to permit the tip portion of the camming surface 65' to move downward into the space formed by forcing the selection bar 46' rearward due to the camming surface 65' against the urging of the resilient member 52'. Thus the selection bar 46' is conditioned for entry into the ball interlock upon restoration by the restoring bail 60', since the selection bar 46' will move forward off the camming surface 65' of the depending portion 64' and go into the active position under the influence of the resilient member 52'. Thus it is possible to depress keys in succession on an open keyboard according to the invention resulting in higher speed keying being possible than with a closed keyboard, and without the danger of double character keying.

As also shown in FIG. 2 the open keyboard according to the invention is arranged to operate a light switch 12' wherein light from a lamp 71 is switched by means of a shutter 72 through apertures 73 onto photoresponsive elements 74. Obviously other switch assemblies may be operated by the selection bars 46', such as for example the electric contact switch assembly 12 as shown in FIGS. 1 and 4, and the conventional magnetic switch array (not shown) comprising windings and movable cores arranged to be positioned by the selection bars.

FIG. 3 illustrates another form of the open keyboard according to the invention which operates similar to the arrangement shown in FIG. 2; the principal difference lying in the construction of the spring assembly wherein the resilient spring member 52'' is an extending portion of the cantilever support spring member 42''. A depending portion 64'' with a camming surface 65'' is present as before, for cooperation with a camming surface in a notch 66'' in the selective bar 46'' in the same manner as for that shown in FIG. 2.

Key sections according to the invention as illustrated in the keyboard arrangement of FIG. 1 are shown in elevation of FIG. 4. As before, the key bars 36 are supported for strictly vertical translation by spring members 41 and 42 and the selection bars are urged forward by means of a resilient member 52. Two bars are shown in FIG. 4, the off bar designated 46a and the near bar designated 46b. Each of the selection bars 46 has a shoulder 66 which is urged up against the cross member 23 in which the raceway 56 for the balls 58 of the ball interlock assembly is arranged. A spring extension 82 of the spring 42 rests in a notch 84 of the selection bars 46. When a key bar 36 is depressed the extension spring 82 forces the near selection bar 46b off the shoulder 66, permitting an upper blade 86 to enter the ball interlock

and allowing the switch 12 to be operated if there is room in the ball interlock for the blade 86 to enter. According to the invention the spring extension 82 bows sufficiently, in FIG. 4(b), to flex over the camming surface 65 of the near key bar 36b and the surface 84 of the near selection bar 46b when the latter is prevented from entering the ball interlock by the prior entrance of the off selection bar 46a. The spring extension 82 flexes sufficiently to allow the depression of the key top 14b and permit restoration of the off selection bar 46a by the restoring bail 60, and the near selection bar 46b remains above the bail 60 as the ball interlock will only permit it to enter a short distance as long as the off selection bar 46a is in the interlock. The bail 60 is normally moving to the home position before the near selection bar 46b is able to enter the interlock, 15 but if for any reason the bail 60 remains below the near selection bar 46b, the latter merely presses on the inclined surface of the restoring bail 60 assisting it in its movement to the home position enabling the subsequent entrance of the near selection bar 46b into the ball interlock in the desired sequence. 20

The electric switch 12, as shown in FIGS. 1 and 4, comprises complementary silver alloy comb shaped electric contact members 90 and 91. The fixed contact members 90 are held in J shaped bus bars 92, and the movable 25 contact members 91 are embedded in an insulating member 93 molded to the permutation bars 46 with the teeth or contact making blades 94 protruding. The movable blades 94 make or break contact as desired with the fixed contact making blades 95 made of silver alloy and held in 30 electric circuit bus bars 92, as shown. The blades 95 which are not required for making the desired coding for a particular switching system are removed in manufacture or in the field as convenient, the structure according to the invention readily lending itself to such alteration. 35

As thus far described the switch 12 comprises fixed and movable contacts for connection by those skilled in the art to satisfy the requirements of the equipment at hand. In a common arrangement, for example, a common contact member 94 is connected to a common bus 92c for applying electric current to others of the busses 92 as may be desired. According to the invention, however, different connections of bus bars 97 may be effected. For example, as shown in FIG. 5, two of the teeth 94s of the comb member 91 may be isolated from the comb by drilling through holes 96 for which pilot depressions 96p have been molded in the insulating member 93. The isolated teeth 94s are then interconnected by a wire 97 in groove 98 molded in the insulating member 93. The wire is soldered to the isolated teeth 94s in holes 99 on the opposite side which are drilled out as needed, pilot holes 99p having been molded in the member 93. 40

While the invention has been particularly shown and described with reference to the preferred embodiments thereof, it will be understood that those skilled in the art many make various changes in the form and details without departing from the spirit and scope of the invention. 45

The invention claimed is:

1. An interlocked open keyboard having a frame, a plurality of key sections and a switch assembly arranged in said frame and a mechanical interlock assembly permitting but one of said key sections to be operated to an active state at any one time, each key section comprising a key bar arranged in said frame for movement in one direction, a key stem and a key top mounted on said key bar, first resilient means urging said key bar to a home position and confining the movement of said key bar to a single degree of freedom, a selection bar arranged in said frame in the same plane of movement as that of said key bar for movement in another direction and coupled to said switch apparatus, and second resilient means urging said selection bar in said other direction into a home position and toward an active position, said selection and key bars having cooperating camming sur-

faces arranged to trip said selection bar for movement to said active position as permitted by said interlock assembly and to hold said selection bar in readiness for said movement against additional deflection of one of said resilient means in the event said selection bar is locked out by said assembly. 5

2. An open keyboard having

a frame,
a key bar arranged in said frame for movement in a given direction,
a resilient member urging said key bar into a home position,
a selection bar arranged for movement in a predetermined direction in response to the movement of said key bar,
a further resilient member urging said selection bar in said predetermined direction into a home position and into an active position in response to movement of said key bar,
camming elements arranged on said key and selection bars and operative against the resilience of one of said resilient members for permitting the movement of said key bar and restraining the movement of said selection bar into said active position, and utilization apparatus actuated by said selection bar. 10

3. An interlocked open keyboard having

a frame,
a key bar arranged in said frame for movement in a given direction,
a resilient member restraining said key bar movement to said given direction and urging said key bar into a home position,
a selection bar arranged for movement in a predetermined direction in response to the movement of said key bar,
a further resilient member urging said selection bar in said predetermined direction into a home position and into an active position in response to movement of said key bar,
camming elements arranged on said key and selection bars and operative against the resilience of one of said resilient members for permitting the movement of said key bar and initiating movement of said selection bar, an interlock restraining the movement of said selection bar into said active position, and utilization apparatus to be actuated by said selection bar. 15

4. An interlocked open keyboard having a frame, a

plurality of key sections and utilization apparatus arranged in said frame and mechanical interlock means permitting but one of said key sections to be operated to a completely active state at any one time, each key section comprising a key bar arranged in said frame for substantially vertical movement, a key stem and a key top mounted on said key bar, first resilient means urging said key bar upward to a home position and confining the movement of said key bar to a single degree of freedom, a selection bar substantially horizontal movement in the same plane of movement as that of said key bar, a potential energy path opening and closing utilization structure arranged in said frame and coupled to said selection bar, and second resilient means urging said selection bar in substantially horizontal movement into a home position and in response to depression of said key bar toward an active position, said selection and key bars having cooperating camming surfaces arranged to initiate movement of said selection bar toward said active position with additional deflection of one of said resilient means in the event said selection bar is locked out by said interlock means. 20

5. An interlocked open keyboard having a frame, a plurality of key sections and utilization apparatus arranged in said frame and mechanical interlock means permitting but one of said key sections to be operated to a completely active state at any one time, each key section comprising a key bar arranged in said frame for substantially vertical movement, a key stem and a key top mount-

ed on said key bar, first resilient means urging said key bar upward to a home position and confining the movement of said key bar to a single degree of freedom, a selection bar underlying said key bar and arranged in said frame for substantially horizontal movement in the same plane of movement as that of said key bar, a potential energy path opening and closing utilization structure arranged in said frame and coupled to said selection bar, and second resilient means urging said selection bar in substantially horizontal movement into a home position and in response to depression of said key bar toward an active position, said selection and key bars having co-operating camming surfaces arranged to initiate movement of said selection bar into said interlock means prior to forward movement into said active position under urging by said second resilient means.

6. An interlocked open keyboard including a frame, two pairs of cross members arranged parallel to each other in said frame and having a multiple of elongated slots therein arranged parallel to each other, a multiple of key bars arranged for movement in one direction in corresponding slots of one of said pairs of cross members and having key stems thereon, a like multiple of selection bars arranged in substantially the same plane as said key bars for movement in a direction substantially normal to said one direction in corresponding slots of the other of said pairs of cross members, said selection bars having shoulders thereon normally bearing on one of the other of said pairs of cross members, said bars having cooperative camming surfaces thereon, an assembly of dual-leaf springs arranged on one of said cross members supporting and urging said key bars upwardly to a home position and having extensions thereon individually contacting corresponding selection bars, an assembly of single-leaf springs urging said selection bars against said one other cross member in said other direction, said springs being the sole means for retaining said bars in said corresponding slots, a mechanical interlock assembly arranged on said other cross member for receiving but one of said selection bars at any one time, key tops individual to and arranged on said key stems, and a switch assembly arranged to be operated by movement of said selection bars.

7. An interlocked open keyboard comprising, a frame having parallel cross members each having a like plurality of elongated slots arranged parallel to each other, a number of key bars arranged in pairs of said slots, a key top for each key bar, an assembly bearing a pair of cantilever spring members for each of said key bars arranged on one of said cross members in contact with the associated key bars urging it to a home position and confining its movement to a single degree of freedom, an interlock assembly having a number of slots therein, a like number of selection bars arranged in pairs of said slots for movement in a direction substantially normal to the direction of movement of said key bars and in substantially the same plane as the associated key bar, each selection bar having a shoulder portion bearing against a common cross member in the home position and a blade portion extending into said interlock assembly, said interlock assembly being arranged to permit but one of said selection bars to move to the active position at

any one operation, an assembly bearing a number of spring members arranged on one of said cross members urging said selection bars into said home position and toward said active position, each of said pairs of cantilever spring members having an extension extending toward the associated selection bar, each of said selection bars having a camming surface underlying the associated cantilever spring extension and arranged to trip said selection bar shoulder off said cross-bar and to permit said extension to bow in the event said selection bar is locked out of movement into said interlock mechanism, a restoring bail arranged crosswise of said frame for restoring said selection bars to said home position, and an electric contact switching assembly operated by said selection bars comprising a number of sets of contact members underlying said selection bars, each of said sets of contact members being in comb-like configuration extending across and beneath said selection bars, a like number of sets of interconnect members, each arranged on an associated selection bar and being in the form of a comb-like configuration having teeth arranged in proximity to the teeth of said contact members for selective contact and interconnecting of the sets of contact members.

8. An open keyboard having a frame, a key bar arranged in said frame for movement in a given direction, a resilient member urging said key bar into a home position, a selection bar arranged for movement in a predetermined direction in response to the movement of said key bar, a further resilient member urging said selection bar in said predetermined direction into a home position and into an active position in response to movement of said key bar, camming elements arranged on said key and selection bars and operative against the resilience of one of said resilient members for permitting the movement of said key bar and restraining the movement of said selection bar into said active position, an electric switch actuated by said selection bar, said switch comprising a plurality of fixed contact members arranged in linear relationship to said selection bar, and a plurality of moving contact members, comprising an elongated comb-like structure of contact making material molded in an elongated insulating structure carried by said selection bar.
